UNITED STATES PATENT OFFICE.

AMELIA E. ANDERSON, OF CINCINNATI, OHIO.

WINDOW.

Application filed December 23, 1922. Serial No. 608,627.

To all whom it may concern:

Be it known that I, AMELIA E. ANDERSON, a citizen of the United States, residing at Cincinnati, in the county of Hamilton and 5 State of Ohio, have invented certain new and useful Improvements in Windows, of which the following is a specification.

My invention relates to steel window constructions wherein part of the sashes are stationary and part of the sashes are adapted to 10 slide sidewise parallel with said stationary sashes.

The objects of my invention are to provide a simple, efficient, convenient, safe and 15 durable window construction; to provide a construction having sidewise-slidable sashes which permits convenient cleaning on the outside from the inside with safety and permits simultaneous ventilation from top-to 20 bottom of the window; and to provide a construction in which the parts are so formed and arranged as to securely protect against the admission of the elements when the window is closed.

25 My invention consists in a steel window frame having stationary sashes, and co-operating sashes adapted to slide sidewise and parallel with said stationary sashes.

My invention also consists in the parts 30 and in the construction, combination and arrangement of parts as herein set forth and claimed.

In the drawings:

Fig. 1 is a perspective view from the inside illustrating my window construction in 35 closed position;

Fig. 2 is an interior elevation showing the window in open position;

Fig. 3 is a horizontal section on the line 40 3—3 of Fig. 1;

Fig. 4 is a vertical section on the line 4—4 of Fig. 2;

Fig. 5 is an enlarged inside elevation 45 partly broken away and representing one of the slidable sashes;

Fig. 6 is a fragmentary view enlarged showing the meeting edges of the slidable sashes and held in closed position by preferred form of latch;

Fig. 7 is a perspective view showing the

shape of the combined supports and weatherstrips for the stationary sashes and also the shape of the tracks on which the slidable sashes are mounted;

Fig. 8 is a perspective view of one of the 55 rollers for supporting the slidable sashes upon the tracks;

Fig. 9 is an outside elevation of a modified construction showing two stationary sashes and two slidable sashes, one slidable sash 60 being in closed position and the other slidable sash in partly open position; and

Fig. 10 is a plan view of the sill, weatherstrips and supports for the stationary sashes and track for the slidable sashes. 65

In the embodiment of my invention, as illustrated and which shows preferred constructions I provide a sill 1 of steel having a flange extending outwardly and downwardly forming apron 2 and having a flange extending downwardly, inwardly and downwardly to form a stool 3 covering the base on which said sill rests. The lower surface of said sill conforms to the surface of the base on which it firmly rests and is secured thereto in any suitable manner. The steel window frame comprises a vertical Z-shaped jamb 4 on each side each connected at its top to Z-shaped head 5, said jambs and head being mitered and welded together at their points of connection forming the upper corners. Said frame has an outwardly extending flange 5' at the top and an outwardly extending flange 4' at each side adapted to be embedded in the surrounding wall. It 70 also has downwardly extending flange 5" at the top and an inwardly extending flange 4" at each side. 75

Each sash comprises vertical channel bars 6, each having an inwardly projecting fold 7 and mitered at each end and connected at top and bottom to horizontal channel bars 8 and 9 of like construction. Each sash is provided with a pane 10 which is held upon one side by projecting fold 7 and on the other side by putty 11 supported by angle putty strips 12 and 13 which are mitered at their ends and are secured to each sash by screws 14. 90

In the construction shown in Figs. 1, 2 and 100

4 I have provided two long lower stationary sashes 15 and 16, two long lower sidewise slidable sashes 17 and 18, two short upper stationary sashes 19 and 20 and two short 5 upper sidewise slidable sashes 21 and 22.

I provide a U-bar weather-strip 23 having one flange thereof extending into the inner vertical channel of each stationary sash to which it is secured by screws 24 and filling 10 blocks 25 mounted on said screws within the channels.

Supporting plate 26 adapted to have its ends engage the jambs 4 has mounted upon its upper side at each end combined 15 weather-strip and support 27 and upon its lower side at each end combined weather-strip and support 28, said supports being secured to said plate by screws 29. Said plate is also provided upon its upper side with 20 combined track and weather-strip 30 extending its full length and upon its lower side with combined track and weather strip 31 extending its full length, said track being secured to said plate by screws 32. The 25 short stationary sashes are each placed in position on said supports 27 extending into its lower horizontal channel and are secured thereto by screws 33.

Each slidable sash is provided with an 30 inwardly extending elongated tongue 34 and is secured to the outer vertical edge thereof by screws 35. Each tongue is so bent as to be spaced apart from said sash a portion of its width with its free edge curved laterally away from the sash. One of each pair of slidable sashes is provided adjacent its meeting edge with a flat projecting weather-strip 36 secured to the outer surface thereof by screws 37 and the other slidable sash of 40 each pair is provided with an elongated weather-strip 38 secured in its inner vertical channel by screws 39 and adapted to project beyond the meeting edge of said slidable sash and into the vertical channel of the 45 meeting edge of the co-operating slidable sash. Each slidable sash is provided in its lower channel with track rollers 40 mounted on axles 41 and track rollers 40' in its upper channels. One of each pair of slidable sashes 50 is provided upon its inner side near its meeting edge with keeper 42 and the co-operating slidable sash is provided on its inner side near its meeting edge with pivotally mounted catch 43 having a suitable handle 55 44 whereby said slidable sashes are held in closed position or conveniently disconnected when it is desired to slide them to open position.

Upon each end of sill 1 I mount combined 60 support and weather-strip 45 and secure it thereto by screws 46.

The upper stationary sashes 19 and 20 and connecting parts as above described are placed into position between the jambs 4 as

shown in Figs. 1 and 4 with depending 65 flange 5' of head 5 extending into the upper horizontal channels of said stationary sashes and to which they are securely fastened by screws 48 and to flange 4" of jamb 4 by screws 47. Each lower stationary sash is inserted in vertical position centrally of opening 49 and is adjusted sidewise with its upper and lower channels fitting over supports 28 and 45, respectively, to which it is securely fixed by screws 50 and 51, respectively. It is 70 also secured to flange 4" by screws 47.

The upper slidable sashes are placed with their meeting edges together and with track 52 resting thereon with its U-shaped portion extending into their upper horizontal 80 channels. Said sashes are then placed in position over track 30 which extends upwardly into their lower horizontal channels when said sashes are adjusted to vertical position whereupon track 52 is secured to head 85 5 by screws 53. When in that position rollers 40 will rest upon track 30 whereby said sashes may be slid sidewise to open or closed position, as desired. The lower slidable sashes are placed with their meeting 90 edges together over track 54 whereupon they are inserted to vertical position beneath track 31 which extends into their upper horizontal channels. Track 54 is then secured in fixed position on sill 1 by screws 95 55.

When either the upper or lower slidable sashes are in closed position as shown in Fig. 3 the U-bar weather-strip 23 will engage tongue 34 a portion of its width leaving an 100 air pocket 56 which serves to insulate and prevent any draft of air through between said tongue and U-bar. It also serves as a cushion when closing the slidable sashes and prevents jarring of the parts. Weatherstrips 36 and 38 effectually form a weather-tight joint at the meeting edges of the 105 slidable sashes.

In the modification illustrated in Fig. 9 the construction of the frame and sashes is 110 the same as the frame and lower sashes of Fig. 1.

With my novel construction the slidable sashes may be opened and closed without in any manner interfering with draperies, 115 floor coverings or other objects placed about the window in the interior of the building. The manner in which each slidable sash is guided and supported precludes the possibility of distortion or sagging thereof thereby resulting in ease of operation and avoiding all sticking and binding of the slidable sashes in the frame.

By employing the U-shaped supports and runways or tracks the sashes are always 125 held in uniform place and form weather tight joints between the window frame and the tops and bottoms of the sashes. The

exterior top and side channels of the stationary sashes receiving the inwardly projecting flange of the head and jambs, respectively, or the U-shaped support and 5 weather-strip and inwardly projecting flange of the jambs, as the case may be, whereby air pockets 57 are formed in said channels results in an absolutely perfect weather tight joint therebetween. The interengaging 10 weather-strips on the stationary and slideable sashes effectively form weather tight joints and prevent moisture or wind from penetrating the same when the slideable sashes are in closed position. The construction 15 is such that weather tight joints are obtained on all sides of the sashes.

Another advantage is obtained by dividing the window into upper and lower sections making it possible in severe weather 20 to open one or both of the upper slideable sashes only to a limited extent, the bottom slideable sashes remaining closed. In this manner perfect ventilation may be obtained. In extremely warm weather it is possible to 25 partly open the window from top to bottom thereby obtaining ample ventilation under all conditions.

The forming of the sashes in the manner described provides an extremely durable and 30 rigid construction. The sidewise slideable sashes cannot be disturbed by a gust of wind thus avoiding the forcible slamming shut of the sashes and the consequent breaking of the glass panes. This construction 35 also avoids the use of pulleys, cords, counterweights, pivoted hangings and hinges which are always troublesome in their operation. The substitution of my construction therefore results in extremely easy and noiseless 40 operation.

Should it become necessary to replace the glass in any of the sashes, if for any reason the same should become broken, it is only necessary to remove the screws 14 which permits the withdrawal of the angle putty strips 12 and 13, whereupon the putty may be removed and the glass easily replaced without removing the sashes from the frame, this being conveniently accomplished with 50 safety entirely from the interior of the building. Furthermore, the glass panes can be conveniently cleaned on the outside from the inside since it is only necessary to adjust the slideable sashes to open position to conveniently reach the outside of the stationary sashes and the outside of each slideable sash can be conveniently reached from the inside when the other slideable sash is in open position. Thus the entire outer surface of the 55 sashes may be conveniently reached for cleaning from the interior of the building without the necessity of standing on the window sill apron and subjecting persons cleaning the windows to the danger of falling.

The upkeep of my novel window construction is practically negligible as no decayable material is employed therein. Another feature of merit is that a substantially complete window may be manufactured and partly assembled ready for easy and convenient installation in the building. If desired also, the interior of the building may be entirely finished before the window is installed. My construction also provides a pleasing and 75 ornamental appearance.

It combines all desirable features that a modern window should have and eliminates all objectionable features, entirely filling requirements that have long been desired for 80 a neat, convenient, practical, safe, durable, substantially noiseless, thoroughly weather proof and economical window.

While I have shown and described particular constructions, it will be apparent that it 85 is capable of some modification without departure from the scope or spirit thereof, as defined in the claims.

What I claim as new and desire to secure 90 by Letters Patent is:

1. In a window, a steel frame comprising a sill, a Z-shaped head, Z-shaped jambs connected to said head, stationary sashes each having a channel in its outer edge and secured in fixed position at top, bottom and one side, a U-bar weather strip secured to the inner vertical edge of each stationary sash, a pane mounted in and secured to each sash, a pair of slideable sashes mounted parallel with said stationary sashes on upper 100 and lower tracks, each slideable sash having a tongue on its outer side adjacent its outer vertical edge and spaced from said sash a portion of its width and adapted when said sashes are in closed position to receive the 105 edge of said U-bar and having a weather-strip on its outer side projecting past its inner vertical edge and its co-operating sash having a weather-strip secured in its meeting edge channel, said weather-strips adapted to project over the meeting edges of said slideable sashes when in closed position.

2. In a window, a steel frame comprising a head, jambs and sill, U-shaped tracks having lateral flanges and mounted on said head and sill, respectively, and a channeled sidewise slideable sash having rollers in its channel to engage the track, stationary sashes mounted in said frame parallel with said sidewise slideable sashes and weather-strips mounted on said sashes to form tight joints therebetween.

3. In a window, a steel frame having an inwardly projecting flange at top and sides and comprising a head, jambs and sill, U-shaped tracks having lateral flanges and mounted on said head and sill, respectively, and a channeled sidewise slideable sash having rollers in its channel to engage the track, stationary sashes mounted in said frame 125 130

parallel with said sidewise slidable sashes and weather-strips mounted on said sashes to form tight joints therebetween.

4. In a window, a steel frame comprising a head, jambs and sill, U-shaped tracks having lateral flanges and mounted on said head and sill, respectively, and a channeled sidewise slidable sash having an inwardly pro-

jecting fold and having rollers in its channel to engage the track, a pane secured to said inwardly projecting fold, stationary sashes mounted in said frame parallel with said sidewise slidable sashes and weather-strips mounted on said sashes to form tight joints therebetween.

AMELIA E. ANDERSON.
